AUTOMATIC CONTINUATOR

Edwin Hopkins, New York, N. Y.

Application June 25, 1929, Serial No. 373,569

5 Claims. (Cl. 274—10)

The chief purpose of my invention is to provide means for playing a plurality of disc phonograph records successively in such manner that when one is finished the playing of the next is begun automatically without delay, in order that the sounds of the successive records will keep in synchronism with a motion picture film of analogous subject matter projected at the same time at a predetermined rate of speed as respects the phonograph records.

Films of motion pictures are customarily of considerably greater length in playing time than disc phonograph records, but I provide successive records and means for transferring from one to the next without losing synchronous relation with the film, which has not hitherto been done.

In my invention I provide a plurality of disc turntables preferably positioned one above the other, with a separate tone arm for each table, and means for automatically lowering such tone arms successively into playing position one after the other at the proper time, and also means for lifting them off at the proper time.

I provide a counting device for each turntable, so arranged that after a predetermined number of revolutions have been made by the turntable, the counting device sets into operation a train of members which has a cycle of operations automatically depositing the tone arm on the new record, and lifting off of the played record its tone arm, and at the same time setting the new record's counting device going.

As most disc records run less than 1,000 convolutions I arrange the counting device to function at 000, or on the next count after 999, a fourth dial for the "1" being needless. If a record has 724 convolutions I set the counter at 276 as the initial point for the first rotation of the record, when the 724 turns of the record are made, starting on the counter after 276, the total will be 1,000, since the first turn of the record registered 277 on the counter and the last 000.

276 may be termed the pre-count number. This I note on the record itself for the guidance of operators as the counter is manually set to the pre-count number before playing begins. Thus the smaller the record the larger will be the pre-count number. Records of different sizes may be played, succeeding each other. This is useful where eliminations are made from a film, as in a re-take of an abbreviated portion a smaller record may be made.

Portions may also be omitted from a record, as, for example, if the precount number of the 724 convolution record is set at 376 instead of 276,

the tone arm will be lifted off 100 turns before the normal end of the record and the next record will be begun. Suitable lengths of motion picture film may be cut out to shorten the film the same running time as the 100 turns omitted from the record.

The apparatus is so arranged that it may be loaded with disc records before starting, all the counters being set, each to the pre-count number of its record. The number of rotations from the beginning of the first to the end of the last will thus be known in advance, and started at an initial point with the film of the same running time, synchronism will be maintained throughout.

As many turntables and tonearms may be provided as desired. Ten turntables playing 4½ minute records would suffice for 45 minutes of performance, as long as an act of a play. My apparatus, however, is provided with means for enabling records to be removed and replaced during operation of another record, and thus it may be run continuously for many hours, one apparatus being adapted to serve two cinematographs alternately if desired. The operator removes a record, positions a new one and re-sets the counter and adjusts the parts so that the new record is automatically turned into at the proper moment.

In addition, when the apparatus finishes with the lowermost record, it functions automatically to begin playing the uppermost record. Thus no matter how long the film may run, records can be run in synchronism with it indefinitely.

Additional features of the invention will be found set forth in detail hereinafter.

In carrying out my invention I find it generally desirable to employ the herein described apparatus, processes and manufactures, but it is to be understood that in carrying out the objects of my invention, less than all of the different means, mechanisms, processes and manufactures herein described may be employed for some uses, or parts only may be employed, or other mechanisms, processes and manufactures similar may be substituted, and while the preferred forms embodying my invention are shown, it is to be understood that many of the structural details may be varied and many changes in details and steps resorted to, without departing from the scope and spirit of my invention, nor do I limit myself to the specific devices, manufactures and processes shown, although I believe them especially suited to the ends to be attained by my invention.

In the accompanying drawings, which are largely diagrammatical and are not to be considered as working drawings but merely as illus-

trations of the principles of the invention, many parts being omitted from particular figures and planes of section being taken approximately only, for the purpose of clearness of illustration of principles; and which form a part hereof, and in which the same reference letters and numerals indicate the same or corresponding parts:

Fig. 1 is a front elevation of the apparatus;

Fig. 2 is a side elevation;

Fig. 3 is a plan of a turntable portion;

Fig. 4 is a sectional plan of a portion of the apparatus, on line 4—4 of Fig. 2;

Fig. 5 is a partial sectional plan of a portion of the apparatus, taken on line 5—5 of Fig. 2;

Fig. 6 is a rear elevation of a portion of the apparatus;

Fig. 7 is a cross sectional plan of the counting device, taken on line 7—7 of Fig. 9;

Fig. 8 is a vertical, sectional, front elevation of the counting device on line 8—8 of Fig. 9; and

Fig. 9 is a vertical, transverse side elevation section of the counting device on line 9—9 of Fig. 8.

Figs. 7, 8 and 9 show some of the connecting parts of the counting device to the rest of the apparatus, and are on a larger scale than the remainder of the drawings.

The various views show certain parts omitted, and other parts included forward of the sectional lines, for clearness of illustration.

Turntables 1, 2, 3 and 4 are driven through mitre gears by vertical shaft 5, and their rotation is counted by counting devices 6, 7 and 8, turntables 1 and 2 functioning in unison simultaneously and being counted by counting device 6.

Turntable 1 is a supplementary table to turntable 2, both playing or remaining idle in unison. Thus an overture orchestral piece may be recorded on record for turntable 1, while vocal effects may appear on record for turntable 2, either simultaneously or interlarded. The apparatus may be so constructed as to provide one or a plurality of supplementary turntables for each counted turntable. These supplementary turntables may contain special sound effects not suitable for recording in a speech record.

The cycle of operations which takes place between record and record includes ten principal functions:

a. The starting of the turntable with the record on it;

b. The depositing of the tone arm needle on the record;

c. The starting of the counting of rotations;

d. The starting of the next lower turntable;

e. The final count of the rotation counting;

f. The depositing on the next lower record of the tone arm needle therefor;

g. The starting of the rotation count therefor;

h. The lifting off of the turntable record just played of its tone arm;

i. The disengaging of power from such turntable; and

j. The disengaging of the counting device thereof.

Upright pillar or frame 9 serves to carry the chief operative parts of the apparatus. Tone-arm lifting-levers 10, 11, 12 and 13 lift and lower the tone arms for the turntables 1, 2, 3, 4. Lifting levers 10, 11, 12, 13 are pivoted to frame 9 at its rear edge. They are held aloft by pivoted stops, which are ordinarily operated automatically, but which may be manually caused to function.

In the attitude or moment of the cycle of op-

erations illustrated all the turntables are loaded with records and all the tone arms are held aloft by the lifting levers 10, 11, 12, 13 so that while the turntables may be starting to rotate in unison, through power from shaft 5, no sound is being heard and no counting of rotations has begun.

Lifting levers 10, 11, 12, 13 have heels 14, 15, 16 and 17 respectively, which are held in non-playing position by pivoted stops 18, 19, 20, 21 respectively. Stops 18 and 19 operate in unison 10 and control levers 10 and 11. They may be manually operated in opposition to spring 22. This permits tone arms for turntables 1 and 2 to be lowered into playing position.

Heels 15, 16, 17 have extension bars 23, 24, 25, 15 which bars have pendant bars 26, 27, 28, whose function is to throw clutch levers 29, 30, 31 into and out of operation, for the purpose of counting the rotations of the turntables by counting devices 6, 7 and 8.

Thus, for example, when stop 19 is thrown out of the way of heel 15, which ascends, bar 26 simultaneously throws clutch lever 29, which starts counter 6 by means to be described.

Records of turntables 1 and 2 being played in unison and rotations of turntable 2 being counted by counter 6 the operator attends the critical spring cranks, 32, 33, 34, which operate automatically in one direction but have to be replaced manually in the other after functioning automatically.

Critical spring bell crank lever 33 is fitted with a pair of arms, 35, 36, forked at the end, the forks serving to shift a sleeve, slidably feathered to shaft 5, which carries a mitre gear transmitting power to the turntable. When arm 37 of bell crank 33 is pushed to the right (as regarded in the view, Fig. 2) critical spring 38 comes into operation, when its critical vertical line is passed, and carries arm 37 still further to the right, causing it to complete its functions by virtue of the power of spring 38.

In the form of operation in which the operator replaces records during operation, the critical spring cranks are normally positioned to the right, except the one controlling the power to the record turntable in rotation. This permits the other turntables to stand idle.

While turntable 3 is playing, crank 34 is manually positioned to the left, the position seen in Fig. 2. Critical spring 39 is of some strength, as one of its functions is to supply force to lift tone arm lever 12. The manual throwing to the left of crank 34 elevates arms 40—41 into a horizontal position. Mitre gear 42 is integral with sleeve 43 slidably feathered to shaft 5 and rotating with it. Sleeve 43 has annular collar 44 by which sleeve 43 is elevated or lowered by forks of arms 40—41. This causes the engagement and disengagement of mitre gears 42—45, 45 being affixed to the end of shaft 46, journalled in frame-pillar 9 and also in lug 48 of bar 47, which bar is affixed to pillar 9 and serves to support turntable 3.

Bar 47 serves to journal shaft 49, which passes through ball bearing 50, on which turntable 3 is positioned. Phonograph disc records 51, 52, 53, 54 rest on turntables 1, 2, 3, 4 respectively. Record 53 has central aperture which fits over shaft 49 in the usual manner. Turntable 3 and upper half of ball bearing 50 are affixed to shaft 49 rotating with it. Mitre gears 55—56 supply power to set the turntable into rotation 55 being affixed to shaft 46. It is to be noted that the phonograph records indicated start at the inner convolution 75

and end at the outer convolution, the opposite of those for home use.

When crank 34 is turned to the left, it is held in the left position by spring 39, because spring 39 has passed the critical vertical line or over-thrown line. The interlocking of mitre gears 42-45 sets turntable 3 in rotation. A record may then be placed on turntable 3, or it may be placed on it before rotation begins. As bevel gears 42 and 45 may be thrown into mesh at any angular attitude, the operator may follow the following process to get the record rotating at the same angular attitude to the shaft 5 as that which the playing record bears.

The initial point of the record may be marked by a white radial line to the periphery. If the two records are not rotating coincidentally one such mark will pass ahead of the other. The lower turntable having gained momentum, the operator disengages gears 42-45 for a brief period until the playing record and the new record come into unison by the gradual lagging of the latter, when he snaps gears 42-45 into mesh again. This has to be done with nicety as a difference of about 8 degrees equals a single frame or individual picture on the film and two frames discrepancy will destroy synchronism. A planetary adjustment may be provided within my invention for this purpose if necessary, to adjust the angular attitudes of shafts 5 and 46.

While record 53 is rotating and being brought into angular unison with record 52 then being played, no counting is taking place for record 53.

Turntable 3 being in rotation with record 53 ready to be played on, record 52 on turntable 2 is being counted, and presently reaches count 1,000. Between counts the counting device members are stationary. When counter 6 moves from registration 999 to registration 000, projection stud 57 rotates $\frac{1}{10}$ of a revolution. Stud 57 contacts with projection 58 of bell crank lever 59, pivoted in lug 60 affixed to frame 9, moving arm 59 towards frame 9. Bell crank lever 59 has arm 61, contoured to escape interference with other members. The end of arm 61 is in contact with angle leaf 62 of pivoted stop 20.

Pivoted stop 20 has arm 63 affixed to shaft 64 working in lugs 65-66 and 67 and held over heel 16 by spring 68, arm 61 turning leaf 62 in opposition to spring 68.

When stud 57 causes bell crank 59 to function and stop 20 to be knocked off heel 16, gravity causes lever 12 to descend and needle 69 thereupon contacts with record 53. As this occurs pendant bar 27 of bar 24 of heel 16 strikes clutch lever 30, throwing counter 7 into action, which then begins to count rotations of turntable 3.

At the same time prong 70 of bar 24 of heel 16 moves upward and strikes the bevelled left surface (as regarded in Fig. 2) of arm 37 of bell crank 33. The weight and momentum of the descending arm 12 is sufficient to carry arm 37 to the right past the critical line of spring 38, which spring then jerks 37 still further to the right till it is stopped by contact with stop peg 11. The striking of the arm 37 by the prong 70 serves also to lessen the impact of the needle on the record so that the point is less likely to be injured. When arms 35-36 of crank 33 descend gears 72-73 are disengaged, which cuts off the power operating turntable 2, which may then come to rest.

Arm 35 carries rod 74 which extends upward to lug 76 of lifting arm 75. During the playing of record 52, lifting arm 75 has been elevated,

since heel 15 has been standing higher than seen in Fig. 2, to enable arm 11 to permit the playing of record 52. Rod 74 slides loosely in aperture 77 of arm 35, and has a stop protuberance or ball at either end, the distance between the stop balls being sufficiently greater than the distance between 35 and 76 when they are horizontal so that there is leeway for 76 to be carried up by bar 23. When arm 35 descends it draws down arm 75, the foot 78 of which rests on bar 23 of heel 15. This depresses bar 23 and lifts tone arm lifting lever aloft to such a point that stop 19 snaps back, driven by spring 22, and takes a position above heel 15 to hold lever 11 aloft, irrespective of arm 76.

Gear 72 is carried on sleeve 78' feathered slidable to shaft 5, and carrying collar 79 to be engaged by forks of arms 35-36.

When heel 15 is depressed and lever 11 lifted, pendant bar 26 returns to its initial non-playing attitude, which allows the disengagement of counter 6 to take place automatically.

At this stage of the cycle, turntable 2 is idle, counter 6 is idle, arm 11 is lifted and idle, and turntable 3 is playing and counter 7 is counting, while crank arm 37 is positioned to the right against stop peg 11. This allows lifting arm 80 to be carried aloft by its foot 81 which rests on bar 24 of heel 16, since play of end balls of rod 82, which extends from arm 40 to lug 83 of lifting arm 80, is sufficient therefor.

The operator may now replace record of turntable 2 and re-set counter 6 to agree with the new record. As shown in Fig. 2 turntable 4 is turning and lever 13 is aloft, held by stop 21 on heel 17.

When record 53 is finished stud 84 of counter 7 will strike projection 85 of bell crank lever 86, pivoted in lug 87 on frame 9. Bell crank lever 86 has contour arm 88 which is in contact with angle leaf 89 of pivoted stop 21. Pivoted stop 21 has arm 90 affixed to shaft 91 working in lugs 92, 93 and held over heel 17 by spring 94, arm 88 turning leaf 89 in opposition to spring 94.

When stud 84 causes bell crank 86 to function and stop 21 to be kicked off heel 17, gravity causes lever 13 to descend and needle 95 thus contacts with record 54 which begins to play. As this occurs, pendant bar 28 of bar 25 of heel 17 strikes clutch lever 31 throwing counter 8 into action, which then begins to count rotations of turntable 4.

At the same time prong 96 of bar 25 of heel 17 moves upward and strikes the bevelled left surface (as regarded in Fig. 2) of arm 97 of bell crank 34. The weight of the descending lever arm 13 is sufficient to carry arm 97 to the right past the critical line of spring 39. This spring then jerks 97 still further to the right against stop 98, which causes arms 40-41 to descend, disengaging gears 42-45 and cutting off the power operating turntable 3, which then comes to rest.

The descent of arm 40 also causes arm 88 to descend, lifting tone arm lever 12 so that record 53 is heard no more, while bar 27 retracting to its initial non-playing position permits lever 30 to retract and disengage clutch from counter 7. The depression of heel 16 by arm 80 allows stop 20 to snap back under influence of spring 68 so that lever 12 will be held aloft irrespective of further retention by foot 81 of arm 80.

At this stage of the cycle, turntable 3 is idle, counter 7 is idle, arm 12 is aloft and idle, turntable 4 is playing record 54 and counter 8 is 75.

counting, while crank 87 is positioned to the right against peg stop 98.

Lifting arm 98 will be carried aloft by its foot 99 resting on bar 25 of heel 17. This is allowed for by play of end stop balls of rod 100, which extends from arm 101 to lug 103 of lifting arm 98.

While turntable 4 is playing it may be assumed that all the other turntables are idle. Turntable 4 being the lowermost the next to be played will be turntables 1 and 2, the uppermost which play in unison as one unit.

Referring to turntable 2, which is reloaded with a fresh record, succeeding and contiguous in sound effect to record 54, it is to be assumed that arm 37 of bell crank 33 is positioned to the right against stop 71, held there by spring 38. This may then be manually thrown to the left position, (as regarded in Fig. 2) which has the effect of setting turntable 2 into rotation, while arm 11 is still held aloft by stop 19 resting on heel 15.

At the conclusion of the playing of the lowermost record, 54, stud 104 of counter 8 will strike projection 105 of bell crank lever 106 pivoted in lug 107 on frame 9. Bell crank lever 106 also has contour arm 108 the end of which is in contact with angle leaf 109 of pivot stop 19. Pivot stop 19 has arm 110 affixed to shaft 111 working in lugs 112, 113, 114, and held over heel 15 by spring 22, arm 108 turning leaf 109 in opposition to spring 22. Shaft 111 thus extends from the lowermost unit to the uppermost and functions at the top in a manner somewhat similar to the way it would function were another turntable placed below turntable 4.

When stud 104 causes bell crank lever 106 to function, and stop 19 to be kicked off heel 15, gravity causes lever 11 to descend and needle 115 contacts with record 52. As this occurs pendant bar 26 of bar 23 of heel 15 strikes clutch lever 29 throwing counter 6 into action, which begins to count rotations of turntable 2.

At the same time prong 116 of bar 23 of heel 15 moves up and strikes bevelled left surface (as regarded in Fig. 2) of arm 117 of bell crank 32. The weight of the descending lever 11 is sufficient to carry arm 117 to the right of the critical line of spring 118. The spring then jerks 117 still further to the right, against peg stop 119, which causes arms 101—102 to descend. To effect this, bell crank lever 32 has arm 120 and lever 121 has arms 101—102 and arm 122. Arms 120 and 122 are connected by rod 123, so that the action is the same as if a critical spring were placed 55 in connection with lever 121.

Mitre gears 124—125 transfer power from shaft 5 to turntable 4 and gear 124 is mounted integral with sleeve 126 which is slidably feathered to shaft 5 and has collar 127, by means of which 55 it may be moved by the forked arms of 101—102, thus throwing gears 124—125 into and out of engagement.

The upward movement of rod 123 depresses arms 101—102 of lever 121, which comes to rest against peg stop 128, while arm 117 comes to rest against peg stop 119. Mitre gears 124—125 are thus thrown out of engagement and turntable 4 comes to rest. Arm 101 through rod 100 draws lifting arm 98 down, through lug 103, its foot 99 resting on bar 25 of heel 17. This lifts lever 13 aloft and pendant bar 28 retracts and allows clutch arm 31 to throw the counter clutch of counter 8 out of engagement.

It is to be noted that bell crank lever 32 has arms 117 and 120 but is not connected to lever

129 which has arms 130—131. Lever 129, however, is mounted concentrically with crank 32 on the same pillar axis, but has no working relation to it by reason of that fact.

Mitre gears 132—133 transmit power to rotate turntable 1. Gear 132 is mounted on sleeve 134, slidably feathered to shaft 5, with annular collar 135, enabling it to be moved by forked ends of arms 130—131.

Lever 129 is connected to arm 35 of bell crank 10 lever 33 by rod 136, so that it moves in unison with and is controlled by crank 33 at all times. Thus when power is turned on or off turntable 2, it will also be turned on or off turntable 1.

Stop 18 is connected to shaft 111 by bar 137 and moves in unison with stop 19. Thus heel 14 of lever 10 is released at all times coincidentally with heel 15 of lever 11.

Lifting arm 138 rests on bar 139 of heel 14 and serves to lift lever 10 aloft when lever 11 is 20 lifted aloft, through arm 138 being connected to lever 75 by rod 140. No counting device is needed for turntable 1 as counter 6 serves for both turntable 1 and turntable 2, turntable 1 being merely an adjunct of turntable 2. Other adjunct turntables may be provided for turntable 2 if desired or for the other turntables.

It will be obvious that any desired number of turntable units may be provided, one above the other, in this manner. With minor modifications 30 two turntables, as 2 and 4 might alone be used, or a dozen units may be provided between them. Thus enough records could be loaded before starting to last for an hour, and the precount numbers being set on the counters the operator 35 need give no attention whatever to it.

Frame pillar 9 is mounted vertically on foundation 141. Rod 5 is journaled in ball bearing socket 142 and lug 143 attached to frame 9. Shaft 144 rises from foundation 141 and supplies 40 power. Foundation 141 may be a phonograph already in use, arranged to operate synchronously with a cinematograph, or shaft 144 may be supplied with power independently and the cinematograph connection made otherwise in any convenient manner.

Shaft 144 transmits power to shaft 145 by mitre gears 146—147. Shaft 145 is journaled in lugs 148—149 and frame 9.

Pillar 150 is mounted on foundation 141 and 50 carries tone arms 151, 152, 153, 154 to play records 51, 52, 53, 54, such tone arms being supported by levers 10, 11, 12 and 13 respectively.

The tone arms are provided with needles 155, 156, 157, 158, 159 respectively and with sound boxes 55 156, 157, 158, 159, which are supported by pillar 150. The other turntables are supported and operated by units and members similar to those shown for turntable 3.

Lifting lever 12 has an adjuster 160 of a vernier character, enabling the tone arm to be set very closely to the location where the needle is to begin playing. After lever 12 descends, tone arm 153 as it plays passes over the inside collar 161 of the vernier adjuster. After lever 12 lifts, 65 the tone arm is replaced in the vernier adjustment saddle manually, which may then be set to correspond with the initial convolution of the new record. The other lifting levers have similar vernier adjustments. Spiral convolutions 70 of the sound groove are indicated at 162 and 163, the middle convolutions being omitted in the drawings. The view of the tone arms on the left side of Fig. 1 is taken in the line of arrow 164 of Fig. 3 while the view of the turntable units 75

and supports is taken in the line of arrow 165 of Fig. 3.

Tone arm lifting lever 12 is integral with spindle shaft 166 pivoted in lugs 167, 168 on frame 9, and integral with heel 16. The descent of lever 12 thus deposits needle 69 on record 53, turns power off turntable 2, lifts tone arm 11 and operates counter clutch of counter 7.

Other lifting levers are similar to 12, except lever 10 which has heel 14 and no parts similar to 10 and 27.

Shaft 145 drives shaft 5 through mitre gears 168—169.

Critical spring 38 is attached to pillar 170, fixed in frame 9, and to pin 171 of arm 37. Critical spring 39 has similar pillar 172 and pin 173. 118 is similarly mounted.

Crank lever 59 is fitted with spring 174 which opposes the action of stud 57. End 61 of crank 59 also works against spring 68 through leaf 62 which thus, at times, reinforces spring 174.

Arm 138 is pivoted at 175 in lug 176 on frame 9. Arm 176 is pivoted at 177 to lug 60 on frame 9. Arms 80 at 178 and 98 at 179 are similarly pivoted. Counter 6 is attached to frame 9 by angle 180. Other counters are similarly attached.

Crank 32 is pivoted on pillar 181 as an axis, crank 33 on pillar 182 and crank 34 on pillar 183 and crank 121 on pillar 184.

Stops in the form of pegs or small pillars are provided for the levers at various points where required, as at 185, 186, 187, 188, 189 and 190, but such peg stops are only illustrated in Fig. 2.

Counter spur gear 191 is free to rotate on shaft 46 but is not integral with mitre gear 45 concentrically mounted which drives shaft 46. Gear 191 has clutch member 192 which engages with clutch member 193 slidably feathered to shaft 46, which is journaled in frame 9 and lug 48.

Lever 30 which has forks 194 is pivoted at 195 in lugs 196. Pendant bar 27 descends and has horizontal member 197 and vertical pendant member 198, all integral, thus allowing 197 to pass below 88. A small leaf spring 199 vertically placed on and parallel to the outer face of member 198 contacts with lever 30. When 27 moves to the right (as regarded in Fig. 7) leaf spring 199 drives 30 to the right in opposition to spring 200, thus causing clutch members 192—193 to come into engagement and start the counter. Spring 200 normally holds 192—193 out of engagement. When heel 16 is depressed and held by pivoted stop, the lower end of 198 is near the surface of frame 9, and 192—193 are disengaged.

The other clutch members are similarly operated.

A form of counting device suited to the apparatus is shown in Figs. 7, 8 and 9. It is arranged to function at 000, that is, next after 999. It is also arranged to be readily adjusted to the pre-count number of the record.

A series of three cylinder dials is provided, having numerals arranged on their outer peripheries. Cylinder dial 201 registers units, 202 registers tens and 203 registers hundreds. Cylinder 203 is mounted on a small diametered spindle 204, which passes through an aperture in the larger hollow spindle 205 of cylinder 202, and both pass through the still larger hollow spindle 206 of cylinder 201, all the spindles thus being concentric. Spindle 206 is journaled in side 207 of framework 208 and rotates on spindle 205, while 205 rotates on 204. Thus 204 is journaled in 205 and in aperture 209 of boss 210, on side 211 of framework 208. A spring 212 presses 203 away

from the boss, the end of the spring resting on a loose friction bearing plate 213 which rests against 203. The end of spindle 204 may be moved inwardly and outwardly in aperture 209 of boss 210, but as spindle 204 is integral with cylinder 203 the cylinder similarly moves longitudinally.

Spindles 204, 205 and 206 are fitted with knurled thumb knobs 214, 215, 216 respectively. When knob 214 is pressed to the left (as regarded in Fig. 7) cylinder 203 moves similarly. Cylinder 202 may then be moved to the left by knob 215 and cylinder 201 by knob 216. If knob 216 is moved to the left first it carries the other cylinders and knobs to the left, while if 215 is moved to the left it carries cylinders 202 and 203 and knob 214 to the left. When manual pressure is released the cylinders and knobs are returned to their normal positions at the right by spring 212.

Spur gear 191 drives spur gear 217 which is mounted on pillar axis 218 set in frame 9. In Fig. 9 gear 42 is omitted. Intermediate spur gear 217 drives primary spur gear 219 of the counter, journaled on the shaft 220 in side 207 of frame 208 and carrying integrally-united disc 222, rotating in hood or well 221 at the rear of the main part of the counter. Disc 222 carries driving stud 223.

At each rotation of shaft 5 disc 222 makes one rotation and turntable 3 makes one rotation. Cylinder 201 is fitted with counting gear 224, having ten notches for the reception of driving stud 223. At each rotation of stud 223, cylinder 201 is driven forward one notch or number, that is $\frac{1}{10}$ of one rotation, the movement being registered by numbers 0 to 9 inclusive on cylinder 201, which is viewed by the eye of the operator in the direction of arrow 225 of Fig. 9.

Cylinder 201 is also fitted with spur gear 226 which has a wide face. Spur gear 226 drives spur gear 227, which has a narrow face, and is mounted on spindle 229 journaled in lugs 230—231 of frame 208. Spur gear 227 carries driving stud 232. Cylinder 202 is fitted with counter gear 233 with 10 notches, for the reception of stud 232. Ten rotations of 222 will thus cause cylinder 202 to be advanced one notch or number.

Cylinder 202 is fitted with spur gear 234, which has a wide face, and which drives spur gear 235, which has a narrow face, and is mounted on spindle 236, rotating in lug 231 and side 211 of frame 208. Spur gear 235 carries driving stud 237.

Cylinder 203 carries counter spur gear 238, having ten notches, for the reception of stud 237. One complete rotation of cylinder 202 thus advances cylinder 203 one notch or number. One hundred rotations of 222 are thus necessary to advance 203 one notch or number.

Cylinder 203 is fitted with stud 239 which carries projection 84, so placed that when the numerals 999 show on the dials projection 84 will be at the top median line, just about to contact with projection 85 of lever 86. The next turn of 191 carries the dials to 000 (or 1,000 if a fourth cylinder for thousands were provided). The next rotation of 191 would produce numeral 1 on the first dial 201 and the projection 84 would pass under projection 85 of lever 86. But at the instant of the count 000 clutch 192—193 is automatically disengaged and the counter stops and does not register beyond 000.

The operator may then set the counter for the next record. If it has 616 convolutions, for example, he will set the dials to read 384. 616 75

added to 384 will bring the counter again to 000, the functioning point for 84 and 85.

The resetting is accomplished by manually thrusting knobs 214, 215, 216 to the left (as regarded in Fig. 7) which carries counter gears out of line of engagement with studs 223, 232 and 237, enabling the cylinders to be set in any desired attitudes free of interference of studs with gears 224, 233 and 238. Owing to the wide faces of the spur gears 226, 234 they do not slide out of engagement with spur gears 227, 235. Thus the driving studs remain in the proper angular locations with respect to their driving cylinders.

Small grooves at 240 across the face of the cylinders are provided into which small rollers as 241 descend, under pressure of leaf springs as 242, as shown in Fig. 9 only. These notches and rollers hold the cylinders in position between driving impulses of the studs. Bottom 243 of frame 208 supports lugs 230-231, sides 207, 211, front 244 and rear wall 245, which rests against frame 9, to which the counter is attached by angle bar 246. Inner plate 247 of hood 221 rests against frame 9.

Intermediate gear 217 may be of any convenient diameter, and so located as to transmit power from shaft gear to primary counter gear. Windows or openings 248, 249 and 250 in thin top of counter enable the figures on the dials to be seen by the operator.

When in operation a slight time interval may elapse between the close of one record and the beginning of the next. As this interval is normally constant, due allowance can be made for it in making the records. Where a quicker and more direct action is desired, an electro-magnet with circuits and switches therefor may be arranged, either to act as a supplement to the mechanical action or to take its place. A form of such means is indicated in Fig. 2, which makes it clear without illustration in the other figures.

Electro-magnet 251 is mounted on standard 252 attached to frame 9. Armature 253 is affixed to arm 41 of bell crank 34, but is held aloft by spring 254, which is of considerably greater strength than critical spring 39. Electric current is provided to energize the magnet from any suitable source. Two switches are provided for turning the current off and on. Switch 255 is so placed as to have a current passed through on action of contour arm 88 of lever 86 functioning, the circuit being broken when arm 88 is in its initial position of rest. Switch 256 is arranged to pass current continuously when lever 59 is at rest, and for some uses is in series with switch 255.

Considering first the case in which the electro-magnet assists the mechanical action: when the counter 7 reaches 000, projection 84 actuates lever 86 and causes arm 88 to close switch 255, energizing electro-magnet 251. It draws down arm 41, which throws power off turntable 3. This also causes rod 82 through arm 80 to depress heel 16 and lift tone arm lever 12 which causes record 52 to be played no more. It also permits clutch arm 30 to retract, cutting off the counting of counter 7. The counting clutch is thus detached so quickly that 84 advances no further, and thus it holds arm 88 in the position in which a circuit is maintained through switch 255. Simultaneously, supplementary foot 257 fitted to arm 97 has assisted arm 88 and leaf 89 in knocking foot stop 21 off heel 17. This permits needle 95 to play record 53 and also causes arm 31 to throw clutch of counter 8 into action. Thus

the electro-magnet has assisted and even hastened the action of the mechanical members. If now contact at switch 255 is broken and the electro-magnet de-energized, spring 254 will overcome 39 and power will be turned on for shaft 46, but without otherwise affecting the action. If, however, the circuit is not broken at 255 and the engagement and energization continue, unit 3 will remain idle.

Contact switch 256 is then arranged in series with the electro-magnet, source of current and switch 255. Before the end of count on record 54, turntable 2 has been started by manual operation of crank 33. When arm 108 strikes leaf 109 at completion of count of record 54, heel 15 is released, which starts record 52 playing by the train of operations previously described and unit 4 becomes idle.

But as electro-magnet 251 remains energized foot 21 does not retract to be in position to hold heel 17 aloft, but 17 is held aloft by spring 118 acting through levers 120, 122 and rod 123. The energized electro-magnet is now holding tone arm 153 aloft although foot 20 is in position to do so.

When count of record 52 is finished projection 57 moves crank 59 and breaks circuit at 256 and the electro-magnet is de-energized. This throws power on to turntable 3, allows 21 to block heel 17 and holds arm 13 aloft. Arm 61 works leaf 62 which knocks stop 20 off heel 16 and allows record 53 to be played; rod 82 being loose and having sufficient play to allow this since 40 is lifted. Counter 6 is thrown out of engagement, arm 11 is lifted and clutch 30 then sets counter for turntable 3 into operation. It is assumed that this counter, 7, was re-set manually in the interval without breaking contact at 255, to agree with the precount number of the new record.

If it be desired to have the electro-magnet act in place of the mechanical elements, as an independent member of the cycle, it is only necessary to remove leaf 89, and to adjust the prongs of switch 255 to hold lever 88 when it passes between them. Lever 88 may then be released manually after switch 256 breaks the circuit.

All the turntables may be fitted with magnets and switches and circuits if desired, in which case critical lever springs 118, 36, 39 may be omitted together with leaves 62, 89 and 109 but feet similar to 257 need to be provided to knock stops off 50 heels 15 and 16.

Switch 258 is provided for any convenient purpose, as stopping the apparatus or switching from one cinematograph to another at the conclusion of the lowermost record, assuming the 55 cinematograph film used up. Switches such as 257, 258 may be utilized, also to cut off the electric circuit of electric tones arms at the conclusion of the playing of the record, and thus to silence the sound a slight interval in advance of the lifting of the needles; in which case the automatic lifting of the tone arm may be omitted and it may be lifted manually, by the operator on each occasion when necessary.

By making gears 146-147 bevel gears of different diameters instead of mitre gears the speed of shaft 5 may be varied as compared with shaft 144 to any extent desired. A planetary system of gears may also be introduced at this point to provide for occasional variations of speed, should synchronism be lost by accident or otherwise.

Occasions arise when it is desirable to make cuts in the motion picture necessitating removal of portions of the film and record. The record may be treated as follows to effect such result.

At the initial point of the record a depression 259 may be placed, which is somewhat wider than the width of a sound groove and somewhat deeper than the depth of a sound groove at its initial point. It gradually narrows and becomes less deep leading up into the first convolution of the sound groove. At the outset the tone arm needle, as 69, is lowered into this depression. Should the elimination of the fore part of the record be desired, this depression may be cut through at a tangent crossing as many sound convolutions as desired and leading into the sound convolution at the point at which it is desired to have the sounds picked up.

15 In case the latter part of the record is to be eliminated the counter may be set to pick up the tone arm where desired which will cause the subsequent groove not to be tracked, the needle being lifted out of the groove. In case a fractional part 20 of the groove is to be eliminated, as the counter only enables the needle to be lifted at each revolution, a portion of the groove may have its sound indentations engraved off.

If the middle portion of the groove is to be eliminated a tangential depression may be cut across a number of convolutions. Depression 260 in belt of convolutions 163 is of this character. After the needle is running in the fourth groove of 163 the fourth groove is cut through and the cut 30 extends across grooves 5 to 12, cutting into 12 but not across it. This skips all the sounds in the convolutions between the fourth and the twelfth and inserts about $\frac{1}{5}$ of a convolution of silence.

If the middle of the groove only is to be played, 35 the fore part may be by-passed by a tangential groove, the middle part may be played and the latter part avoided by lifting the tone arm through the instrumentality of the counter.

The tangential by-pass may be made of material pasted on the surface of the record, with a 40 needle groove leading up from the sound groove and the groove in the pasted-on material carrying the needle across the grooves to be eliminated and back down into the sound groove to be played. 45 The pasted-on material may be subsequently removed restoring the record to its original condition. Local requirements of censorship may be met in this manner, without mutilating the record.

50 Another method of skipping the middle is to use two copies of a record on adjoining turntables. The first tone arm on reaching the middle is lifted by the counter train. The tone arm of the next turntable is deposited on the duplicate at a 55 point past the middle as selected, being adjusted by the vernier or a tangential initial by-pass as 259 cut in the record past the middle, or such a by-pass pasted on.

If a silent space is desired in a record without 60 cutting the film, three turntables may be used, the middle one carrying no record but arranged for a short counting with a blunt needle on a circular groove in the turntable, or else sound grooves may have their indentations engraved off, 65 or a by-pass may be pasted on have the same number of convolutions as the underlying sound grooves and then leading back into the record.

What I claim is:

1. A phonograph comprising a plurality of 70 turntables positioned concentrically one above the other adapted to rotate in horizontal planes and be driven from a common source of power; such a common source of power; each of such turntables provided with a tone arm; each of such 75 turntables provided with a counting device adapt-

ed to be manually set to count a predetermined number of counts and thereupon to operate; such operation adapted to set in motion a train of members; such a train of members comprising means to perform a cycle of operations comprising 5 the depositing of the tone arm and needle of the next record below on its record to begin its playing; the beginning of the counting of its rotations; the disconnection from the common source of power of the turntable of the record priorly 10 played; the disengagement of its counter and the lifting of its tone arm from its record; and means whereby the counter of the lowermost turntable, on the completion of a predetermined number of counts when its turn comes, sets in motion 15 a train of members adapted to effect a similar cycle of movements in respect to the lowermost turntable and the uppermost turntable; and such train of members; whereby to effect the repetition 20 of such cycles of movement between the various successive records one after the other in an indefinite succession, and means for manually re-setting such counters, inserting new records and turning power on such turntables one by one after the completion of an individual cycle of 25 movements.

2. In apparatus of the class described having a plurality of turntables adapted each to carry a phonograph record, and records therefor with automatic means adapted to cause the discontinuance of the playing of the record of one turntable and coincidentally cause the beginning of the playing of the next turntable record, a turntable with a tone arm supplementary to one of the turntables in the train of turntables set forth, 30 such supplementary turntable and tone arm adapted to function in unison therewith, and automatic means adapted to effect such unitary operation. 35

3. In apparatus of the class described comprising a plurality of turntables with a train of members 40 between each pair of adjoining turntables adapted to automatically cause the playing of the first to discontinue and the playing of the second to be begun coincidentally, electrical means for causing such train of members to function thereaccording, 45 comprising an electro-magnet, a circuit therefor, switches for such circuit and a source of electrical current therefor; such electro-magnet adapted to be energized upon the completion of the count of a counter of the class described with which it is 50 associated; such an association comprising a switch in the circuit adapted to close such circuit and energize such magnet upon the completion of such count; said trains of members of the class 55 described between adjoining turntables; a tone arm lever for each record turntable, a critical spring bell crank lever fitted with a supplementary foot adapted to release the heel of the tone arm lever of the following record turntable; such electro-magnet adapted to cause such bell crank lever to function upon such magnet being energized; whereby to effect the functioning of the train of members actuated from such bell crank lever action; and a supplementary contact switch in such 60 electrical circuit having contacts adapted to be separated and break such circuit and de-energize such magnet upon the completion of the count of a counter of a record subsequent to the following record, and/or, electrical tone arms for such 65 phonograph with switches adapted to be turned and contacts thereby adapted to be broken on the completion of the counting of the turntable, whereby to discontinue vibrations from such tone arms on completion of such predetermined counting of rotations. 75

4. In a phonograph of the class described, detachable means adapted to attach such phonograph to a phonograph to serve as a foundation, with means adapted to cause the power of such foundation phonograph to operate such described phonograph hereof, and/or supplementary means for changing the speed of such phonographs with

respect to each other for limited times to limited extents comprising a planetary gear system intermediate such phonographs.

5. The matter of claim 4 and a cinematograph adapted to be detachably attached to said foundation phonograph. 5

EDWIN HOPKINS.
